Inventor:

R. Geldis

United States Patent Office.

R. M. SELDIS, OF NEW YORK, N. Y.

Design No. 2,835, dated November 19, 1867.

DESIGN FOR A SATCHEL.

The Schedule referred to in these Letters Patent and making part of the same.

TO ALL WHOM IT MAY CONCERN:

Be it known that I, R. M. SELDIS, of New York, in the county and State of New York, have invented new and original Design for Satchels; and I do hereby declare that the following is a full, clear, and exact description thereof, which will enable others skilled in the art to make and use the same, reference being had to the accompanying drawing, making part of this specification.

The drawing represents a perspective view of my satchel.

This invention relates to a new design for ladies' satchels, and consists in covering a satchel, A, of ordinary or suitable description and arrangement, with fur on both sides, and in suspending from the under side of the satchel a muff, B, which is covered with fur of the same kind as that which covers the satchel. The lower edge of the muff is ornamented by a fringe, C, made of Angora or other fine hair, as shown. Cords and tassels D are suspended from the ends of the muff.

What I claim as my invention, and desire to secure by Letters Patent, is—

The design for satchels herein shown and described.

R. M. SELDIS.
